MOTOR BOAT BODY

Kalman Szabadi, Vac, Hungary, assignor to Novex
Talalmanyfejleszto es Ertekesito, Budapest, Hungary

Filed Sept. 4, 1974, Ser. No. 503,485

Claims priority, application Hungary Mar. 6, 1974

Term of patent 14 years

Int. Cl. D12—06

U.S. Cl. D12—62

FIG. 1 is a perspective view of a motor boat body of my new design;

FIG. 2 is a front elevational view thereof;

FIG. 3 is a top plan view thereof;

FIG. 4 is a side elevational view thereof;

FIG. 5 is a rear elevational view thereof;

FIG. 6 is a bottom plan view thereof;

FIG. 7 is a perspective view of another embodiment of the motor boat body of my invention;

FIG. 8 is a front elevational view thereof;

FIG. 9 is a top plan view thereof;

FIG. 10 is a side elevational view thereof;

FIG. 11 is a rear elevational view thereof; and

FIG. 12 is a bottom plan view thereof.

I claim:

The ornamental design for a motor boat body, substantially as shown and described.
